UNITED STATES PATENT OFFICE.

EARL M. DAVIS, OF ROCHESTER, NEW YORK, ASSIGNOR TO HICKOK MANUFACTURING COMPANY, INC., OF ROCHESTER, NEW YORK, A CORPORATION OF NEW YORK.

DESIGN FOR A BELT-BUCKLE FRAME.

Application filed October 7, 1921. Serial No. 506,203. Term of patent $3\frac{1}{2}$ years.

To all whom it may concern:

Be it known that I, EARL M. DAVIS, a citizen of the United States, residing at Rochester, in the county of Monroe and State of New York, have invented a new, original, and ornamental Design for a Belt-Buckle Frame, of which the following is a specification, reference being had to the accompanying drawing, forming part thereof.

In the drawing:

Fig. 1 is a front face view of the belt buckle frame, showing my new design; and

Fig. 2 is a view of the rear side of said frame.

I claim:

The ornamental design for a belt buckle frame, as shown.

EARL M. DAVIS.
